UNITED STATES PATENT OFFICE

1,983,594

FASTENING-SUPPLYING APPARATUS

Hugh E. Briegleb, St. Clair, Mo., assignor to
United Shoe Machinery Corporation, Paterson,
N. J., a corporation of New Jersey

Application August 8, 1932, Serial No. 627,877

16 Claims. (Cl. 1—39)

My invention relates to the supplying of fastenings, it being particularly concerned with apparatus for delivering nails for use in heel-attaching machines and the like.

5 When a nail-feeder or other fastening-distributor, such as that of Letters Patent of the United States No. 1,657,630, Lund, Jan. 31, 1928, is provided with means for causing the discharge of successive loads of nails as a result of direct 10 actuation of its nail-roll or discharge device by the transferring or loading mechanism to which it delivers, a discharge-controlling arrangement of this character being disclosed in Letters Patent of the United States No. 1,768,831, Dostie, July 15, 1930, the power means for actuating the discharge-roll and which stops the nail-advancing movement of the distributor-raceway, as is illustrated in the first-mentioned patent, is absent from the apparatus. Unless means is taken to 20 prevent it, the shake of the raceway will continue during discharge, with a possible tendency to displace the nails from the roll.

The present invention has as an object the provision of simple and effective means for controlling the operation of a fastening-distributor, this means especially lending itself to co-operation with the roll-actuating means of the Dostie patent. This object I attain by transmitting the movement of the loading or transferring mechanism, ordinarily as caused by an operator, through a movable member, as the sole source of power, to apply the force created by the operator to both the discharge device for the fastenings and to means for controlling the movement of the raceway. For this purpose, I prefer to provide a member movable by the loading mechanism with connections which both oscillate the roll which effects discharge and govern the raceway-oscillating mechanism. 30 These connections are shown, in the present instance, as from the loader-actuated member, appearing as a rod, to the discharge-roll and from said roll to the clutch or similar means through which the raceway-oscillating mechanism is driven. By these connections, the control of the raceway-movement is rendered entirely independent of the power-operation of the apparatus. Not only may the raceway-movement be stopped as the nails are discharged from 40 the roll, but the other power-driven elements of the apparatus may be brought to rest, thus removing all opportunity for the introduction of nail-disturbing effects. This I bring about by causing the travel of the transferring or loading means to communicate its movement to a mem-

ber which causes the disengagement of a clutch transmitting power to the main driving shaft of the apparatus. To correctly position the discharge device with respect to the raceway and to maintain the proper relation between the movement of said device and that of the raceway-controlling means, means is preferably provided for simultaneously varying the effect of the loader-actuated member upon the discharge device and controlling means, as by altering its 10 effective length.

In the accompanying drawing is illustrated a particular embodiment of the invention.

Fig. 1 showing in perspective the delivery portion of a nail-distributor generally resembling 15 that of Lund, while

Fig. 2 is a side elevation of the delivery-end of such distributor, together with a loader-arm which receives nails from the distributor for transfer to the nailing mechanism of a heeling 20 machine and actuating connections from the loader-arm to the distributor.

At 10 may be seen the nail-conducting raceway of a distributor D. The nails are delivered to raceway-grooves 12 by a rotatable drum or other power-driven means (not illustrated) and are caused to travel down the grooves by the oscillation of the raceway. For this purpose, said raceway is pivoted, as at 14, upon levers 16 fulcrumed upon the frame 18 of the distributor and rocked through connecting-rods, one of which appears at 20, it being driven by an eccentric 22 upon a main shaft 24 journaled transversely of the frame. Power may be applied to the shaft through a belt-pulley 26 and clutch 28. This clutch is held normally in engagement, so the shaft is rotated, by a spring 30. Disengagement may be effected by a hand-lever 32 fulcrumed upon a bracket 34 projecting from the frame, and this separation of the clutch members may be maintained, as when it 30 is desired to fully stop the operation of the apparatus, by a latch 36 upon the lever, which enters a notch in a projection 38 from the bracket. All the power-driven elements of the distributor are preferably actuated from the shaft 24. Gearing 40 may be utilized to turn the nail-drum, and gearing 42 may oscillate the usual clearing fingers 44 co-operating with the raceway.

To discharge the nails from the raceway in successive loads, the grooves 12 deliver through openings 46 in a roll 48 journaled transversely of the raceway for oscillation between a receiving position, in which the openings are aligned with the grooves, and a delivering position, as shown in Fig. 2, the openings now being inclined down-

wardly so the nails pass by gravity through tubes 50 to enter openings in a loader-block 52, by which they are to be transferred to the nailing mechanism of the machine supplied. The block 52 is 5 carried by a loader-arm 54 mounted to turn about a vertical spindle 56 fixed in the frame of the machine supplied, and movable by the operator between positions for the reception of the nails from the distributor-tubes 50 and the delivery of 10 said nails to the machine. Upon the upper side of the loader-arm is secured a member on which is a cam-surface 58 arranged to strike, as the loader-block approaches the receiving end of its travel, the contact-portion 60 of an actuating rod 15 62 mounted to reciprocate vertically in a bracket 64 secured to the spindle 56. To the upper extremity of the rod 62 is pivoted a rack 66, guided in its movement by an arm 68 turning upon the raceway-frame. A spring 69, joined to the rack, 20 draws the rod 62 normally down for actuation by the cam-surface 58. The rack meshes with a pinion 70 fast upon the discharge-roll. To the end of the discharge-roll opposite the pinion is secured a cam 72, which engages, as the roll oscillates, a plunger 74 guided for reciprocation upon the frame 18. A helical spring 76 surrounds the plunger, urging it toward the cam. Threaded into the opposite extremity of the plunger is a contact-screw 78, against the head of which bears 25 a contact-block 30 carried by the inner end of the hand-lever 32.

Upon starting the apparatus in operation, the latch of the hand-lever 32 is released from the member 38, allowing the spring 30 to cause the 30 engagement of the clutch 28. The pulley 26 being constantly driven by its belt, the shaft 24 now turns, producing rotation of the nail-drum through the gearing 40 and delivery from said drum to the raceway-grooves 12; the oscillation 35 of the raceway through the eccentrics 22, with the consequent forward travel of the nails along the grooves; and movement of the clearing fingers 44 through the gearing 42. The roll 48 remains at rest, with its openings 46 in registration with the raceway-grooves, so it receives a load of nails 40 therefrom. When the operator is ready to perform a nailing operation, the loader-arm 54 is swung manually into nail-receiving position, with the block 52 beneath the lower ends of the distributor-tubes 50. During this movement, the cam-surface 58 upon the loader-arm strikes the contact-piece 60 of the rod 62, elevating said rod and, through the gearing 66, 70, turning the discharge-roll. The cam 72, rotating with the roll, 45 has such a contour that it rapidly forces the head of the screw 78 terminating the plunger 74 against the contact-end 30 of the lever 32 to separate the members of the clutch 28, but without engaging the latching members 36 and 38. Rotation of the shaft 24 is thus stopped, and the movement of the nail-drum, raceway and clearer is 50 discontinued. When all these elements of the nail-feeding means are at rest, the final travel of the loader-arm to its extreme nail-receiving position completes the rotation of the discharge-roll at a time when the apparatus is entirely free from vibration and there is no danger of so jarring nails upon the roll that they waste or clog. When the operator causes the delivering movement of 55 the loader-arm after the nails have been received in the block, the roll 48 is restored by the spring 69 to its normal relation, the cam 72 turned so the spring 76 may retract the plunger 74, and the lever 32 released to permit the spring 30 to 60 again engage the clutch 28 to start the nail-feed-

ing operations. At any time it is desired to fully stop the operation of the apparatus, the lever 32 is shifted by the operator to the maximum extent to disengage the clutch, it being latched at 5 33. I prefer to form the rod 62 in sections, with a shiftable connection at 82, so its effective length may be varied. This allows an initial angular adjustment of the roll 48 about its axis, to correctly align its openings 46 with the raceway-grooves. The screw 78 of the plunger may be varied in position to independently determine the time of disengagement of the clutch, it being noted that, once the latter adjustment is made upon setting up the apparatus, the adjustment at 82 affects the roll and cam-actuated plunger simultaneously, so the proper relation between the roll-oscillation and clutch-release may be maintained. 10

Specific reference has been made to the nail-distributor of the Lund patent, which is designed for feeding at the same time nails of different 15 lengths. It is to be understood, however, that my invention is equally applicable to a single-length nail-distributor.

Having described my invention, what I claim as new and desire to secure by Letters Patent of 20 the United States is:

1. The combination with fastening-feeding mechanism having a movable raceway, a discharge device and means for controlling the movement of the raceway, of means movable by an operator to transfer fastenings from the feeding mechanism, and a member through which the force created by the operator is applied to the discharge device and to the controlling means.

2. The combination with fastening-feeding 35 mechanism having a movable raceway, a discharge device and means for controlling the movement of the raceway, of means movable to transfer fastenings from the feeding mechanism, a member through which the movement of the 40 transferring mechanism is transmitted to the discharge device, and connections to the discharge device for governing the controlling means.

3. The combination with fastening-feeding mechanism provided with an oscillatory discharge-roll, a main driving shaft and a clutch through which power is applied to the shaft, of transferring means movable by an operator to receive fastenings from the feeding mechanism, and a member movable by the transferring means 45 and utilizing the force created by the operator for oscillating the discharge-roll and disengaging the clutch.

4. The combination with a nail-distributor having an oscillatory raceway, an oscillatory discharge-roll to which nails are delivered from the raceway and mechanism for oscillating the raceway, of loading mechanism movable into position to receive nails falling from the discharge-roll, a member movable by the loading mechanism, connections to the member for oscillating the discharge-roll, and connections to the discharge-roll for governing the raceway-oscillating mechanism.

5. The combination with a nail-distributor having a movable raceway, a movable discharge-roll 65 and actuating means for the raceway, of a loader-arm movable by an operator into nail-receiving position at the distributor, a rod movable by the loader-arm, and means for transmitting the force applied by the operator to the rod to both 70 the discharge-roll and raceway-actuating means.

6. The combination with a nail-distributor having a movable raceway, a movable discharge-roll and actuating means for the raceway including a clutch, of a loader-arm movable into nail-receiving 75

ing position at the distributor, a rod movable by the loader-arm, gearing connecting the rod and discharge-roll, a cam rotatable by the roll, and connections movable by the cam for disengaging 5 the clutch.

7. The combination with fastening-feeding mechanism having a movable raceway, a discharge device and means for controlling the movement of the raceway, of means movable to transfer fastenings from the feeding mechanism, a member through which the movement of the transferring means is transmitted to the discharge device and to the controlling means, and means arranged to vary simultaneously the effect 10 of the member upon the discharge device and controlling means.

8. The combination with a nail-distributor having an oscillatory raceway, an oscillatory discharge-roll to which nails are delivered from the 15 raceway and mechanism for oscillating the raceway, of loading mechanism movable into position to receive nails falling from the discharge-roll, a member movable by the loading mechanism, means for varying the effective length of the 20 member, and connections to the member for both oscillating the discharge-roll and governing the raceway-oscillating mechanism.

9. The combination with a nail-distributor having an oscillatory raceway, an oscillatory discharge-roll to which nails are delivered from the 25 raceway and mechanism for oscillating the raceway and including a clutch, of loading mechanism movable into position to receive nails falling from the discharge-roll, connections movable by the loading mechanism and acting upon the discharge-roll, means movable with the discharge-roll for disengaging the clutch, and means arranged to vary the effective length of an element 30 of the connections.

40 10. The combination with a nail-distributor having an oscillatory raceway, an oscillatory discharge-roll to which nails are delivered from the raceway and mechanism for oscillating the raceway, said mechanism including a clutch and a lever movable by the operator to disengage the clutch, of loading mechanism movable into position to receive nails falling from the discharge-roll, and connections movable by the loading mechanism into contact with the clutch-lever.

50 11. The combination with a nail-distributor having an oscillatory raceway, an oscillatory discharge-roll to which nails are delivered from the raceway and mechanism for oscillating the race-

way, said mechanism including a clutch and a lever movable by the operator to disengage the clutch, of loading mechanism movable into position to receive nails falling from the discharge-roll, and connections movable by the loading mechanism into contact with the clutch-lever, said connections including the discharge-roll.

12. The combination with a nail-distributor having an oscillatory raceway, an oscillatory discharge-roll to which nails are delivered from the 10 raceway and mechanism for oscillating the raceway, said mechanism including a clutch and a lever movable by the operator to disengage the clutch, of loading mechanism movable into position to receive nails falling from the discharge-roll, connections movable by the loading mechanism into contact with the clutch-lever, said connections including the discharge-roll. 15

13. In a nail-distributor, a movable raceway, a movable discharge device, means for moving the 20 raceway, and means operable by the discharge device for stopping the movement of the raceway.

14. In a nail-distributor, an oscillatory raceway, an oscillatory discharge-roll, a power-shaft, a clutch through which power is applied to the 25 shaft, connections to the shaft for oscillating the raceway, and means movable by the discharge-roll for disengaging the clutch.

15. In a nail-distributor, an oscillatory raceway, an oscillatory discharge-roll, a cam movable by 30 the roll, a power-shaft, a clutch through which power is applied to the shaft, a lever for disengaging the clutch, connections to the shaft for oscillating the raceway, and a plunger movable by the cam and acting upon the lever.

40 16. The combination with fastening-feeding mechanism having a movable raceway, a discharge device for the fastenings and means for controlling the movement of the raceway, of means movable to transfer fastenings from the 45 feeding mechanism, a member movable under the control of the transferring means, and connections transmitting the movement of the member as the sole means of applying power to actuate both the discharge device to effect the discharge 50 of the fastenings and the controlling means to stop the movement of the raceway.

HUGH E. BRIEGLB.
